END STANDARD FOR A GUN RACK

George J. Smith, Birmingham, Ala., assignor to
Just-O Corporation

Filed May 21, 1970, Ser. No. 23,088

Term of patent 14 years

Int. Cl. D6—99

U.S. Cl. D33—3

The single figure of the drawing is a perspective view of one element of an end standard for a gun rack showing my new design, the side not shown is like the side shown while the back is plain and unornamented.

I claim:

The ornamental design for an end standard for a gun rack, as shown and described.
